TO THE NATIONAL-ACME MANUFACTURING COMPANY, OF CLEVELAND, OHIO, A
CORPORATION OF OHIO.

PUNCH.

1,157,260.

Specification of Letters Patent.

Patented Oct. 19, 1915.

Original application filed July 21, 1914, Serial No. 852,168. Divided and this application filed December 10, 1914. Serial No. 876,408.

To all whom it may concern:

Be it known that we, OSCAR A. SMITH and BENJAMIN F. RINDFLEISCH, citizens of the United States, residing at Cleveland, in the county of Cuyahoga and State of Ohio, have invented certain new and useful Improvements in Punches, of which the following is a specification.

This invention relates to punches for use in the castellation of nuts and adapted for use in presses such for instance as that shown in our contemporaneously pending allowed application Serial No. 852,168, filed July 21, 1914, of which the present application is a division, the object of the invention being to provide an improved punch of this character by means of which the nuts may be punched from the center toward the outside, and which punch is very much stronger than punches ordinarily used for this purpose and very durable in use.

Another object of the invention is the provision of an improved punch holder having means for preventing endwise and sidewise play of the punch.

Ordinarily the punches used for castellating nuts are very light, usually being no wider than the width of the slot to be punched, and in consequence it is impracticable to punch the nuts from the outside toward the center, because, owing to the comparative narrowness of the punch and the lightness of its construction, which is necessary in order that the punch pass into the slot, the punch quickly collapses and wears out, and so far as we are aware no practical means have been devised by means of which a heavier punch may be used.

In the drawings accompanying and forming part of this specification, Figure 1 is a perspective view of this improved punch and its holder; Fig. 2 is a side view of the punch and showing the means for preventing endwise play of the punch; Fig. 3 illustrates a perspective view and a cross section of the punch proper; and Fig. 4 is a sectional view illustrating a part of the press with which this improved punch is adapted for use and showing the position of the punch relative to the die and the feed plunger.

Similar characters of reference indicate

corresponding parts in the different figures of the drawings.

The punch 2, which is intended to operate 55 in a direction transverse to its length, that is with the punch in a horizontal position, comprises a lengthwise extending shank having at one side midway of its width a lengthwise extending rib forming at its forward end a cutting portion or point, which cutting portion has parallel or substantially parallel sides so that such cutting portion is of the width of the slot to be punched, and as this point must be narrow to correspond 60 with the size of slot desired it follows that unless such punch is materially reinforced it is very weak and inefficient, it being understood of course that different sizes of slots require different sizes of punches. The 65 lengthwise extending rib enables the punch as it becomes worn at its cutting end to be repeatedly re-sharpened. The punch is formed in such a manner that it widens out 70 considerably just back of the point, thereby 75 making a very much stronger punch than the ordinary punch, which is, as stated, usually of the same thickness as at the point. In the present instance the punch is shown with a rounded tapered surface tapering 80 from the thickened body 4 toward the point. In the present improvement the punch tapers from the sides thereof toward the cutting end, and also tapers from one, as the top, side thereof toward the cutting end, 85 thus providing what may be described as transversely tapered surfaces. By means of this construction a very heavy, rigid and reinforced punch is obtained. This punch is carried by a punch holder in the form of 90 an arm 5 which is pivoted on a shaft 6, which shaft is supported on a bearing block 7 carried by the punch press, and the shaft is held in position on such block by a bearing cap 8, which is provided with elongated slots 95 9 so as to render the cap capable of sliding on bolts (not shown) adapted to pass through holes 10 in the bearing block 7, thereby permitting the bearing cap to be slid off to permit the pivot or shaft 6 and 100 the punch arm to be removed and replaced. A lock block 11 detachably carried by the holder 5 holds the punch in position sidewise, while a cylindrical lock block 12,

through which passes an adjusting screw 13, holds it in position endwise, the lock block 12 fitting into a groove 14 of the holder at each side of the punch. By means of this 5 cylindrical lock block 12 and adjusting screw 13 it is found practical to prevent the punch from working out of its arm or holder endwise, as the bearing of the cylindrical lock block 12 in its curved grooves makes 10 the lock positive, while the adjusting screw 13 permits of any desired relation between the punch and the cylindrical block.

Ordinarily in the operation of a press of the character shown in the aforesaid application the ram would strike on the top of the punch arm at the point *a*, which is a considerable distance removed from the working point of the punch, and the continual action of the power at a point so far 15 back of the actual cutting point would have a tendency to bend the point of the punch upward and destroy its usefulness. This disadvantage is entirely eliminated by the provision of means which enables the power to be applied at approximately the cutting 20 point of the punch, in that while the stroke of the ram is still delivered at the point *a* it is delivered in such a manner that it is transmitted adjacent to the cutting point of 25 the punch, and for this purpose a hardened cylindrical ram extension 15 is provided, this extension being set into the punch holder or arm on an angle so that while the 30 top of this extension is some distance back from the point of the punch yet the power will be applied to the punch within a short 35 distance from its point. This ram extension 15 extends somewhat above the punch carrying arm, so that the ram will always 40 strike on the end of the extension instead of striking on the top of the punch arm. The extension 15 is loosely fitted in the arm and transmits the power directly from the ram to a point adjacent to the cutting point of 45 the punch, and consequently prevents any bending of the punch during its operation. Moreover, owing to the manner of supporting 50 the punch, which makes possible the distance between the point of the punch and its pivotal support 7, the punch, in traveling from the bore of the nut outwardly, travels practically in almost a straight line. In other words, while the horizontally located 55 punch moves in an arc of a circle, yet the length of the radius of this arc is such that the point of the punch moves in almost a straight line, thus resulting in the production of a slot having its bottom almost flat.

From the foregoing it will be observed 60 that not only have we provided a punch which is very much stronger and more durable than any of the punches heretofore in use, but by reason of the fact that the punch is not connected in any way with the ram or 65 ram slide of the press, or with the power

driven shaft, any lost motion of the ram or the ram slide, or the shaft, or at the pivotal point of the punch, does not affect the action of the punch, and especially is this so because the application of the power of the 70 ram on the punch is so much closer to the punching end of the punch than to its pivotal point.

We claim as our invention:

1. A punch adapted to operate in a direction transverse to its length and having along one side face thereof a rib-formed cutting portion having parallel side walls. 75

2. A punch adapted to operate in a direction transverse to its length and having a 80 rib-formed cutting portion having parallel side walls, said rib-formed cutting portion extending lengthwise of the punch along its underside.

3. A punch adapted to operate in a direction transverse to its length and having a 85 rib-formed cutting portion having parallel side walls, said rib-formed cutting portion extending lengthwise of the punch and midway thereof.

4. A punch adapted to operate in a direction transverse to its length and having along one side face thereof a rib-formed cutting portion having parallel side walls, said rib-formed cutting portion terminating in a 90 widened shank.

5. A punch adapted to operate in a direction transverse to its length and having along one side face thereof a rib-formed cutting portion having parallel side walls, said 100 rib-formed cutting portion terminating in a widened shank provided at the forward end thereof with a bevel portion.

6. A punch adapted to operate in a direction transverse to its length and having along one side face thereof a rib-formed cutting portion having parallel side walls, said rib-formed cutting portion terminating in a 105 widened shank provided at the forward end thereof with portions tapering inwardly 110 from the sides of the widened portion of the shank.

7. A punch adapted to operate in a direction transverse to its length and comprising a lengthwise extending shank having at one 115 side thereof a lengthwise extending rib provided with parallel side walls forming at the forward end of the punch a cutting portion.

8. A punch adapted to operate in a direction transverse to its length and comprising a lengthwise extending shank having at one side thereof a lengthwise extending rib provided with parallel side walls forming at the 120 forward end of the punch a cutting portion, said rib being located midway of the 125 width of the shank.

9. A punch adapted to operate in a direction transverse to its length and comprising a lengthwise extending shank having at one 130 side thereof a lengthwise extending rib pro-

vided with parallel side walls forming at the forward end of the punch a cutting portion, said rib being located midway of the width of the shank and said punch having a 5 tapered forward edge the apex of which terminates above the cutting edge of the rib.

10. A punch adapted to operate in a direction transverse to its length and having along one side face thereof a rib-formed 10 cutting portion having parallel side walls, a punch holder adapted to carry said punch, and means for locking the punch against endwise play.

11. A punch adapted to operate in a direction transverse to its length and having along one side face thereof a rib-formed cutting portion having parallel side walls at its cutting portion, a punch holder adapted to carry the punch, and adjustable 20 operating means carried by the punch and holder for locking the punch against endwise play.

12. A punch holder adapted to carry a punch, and adjustable means in the rear of 25 the punch for locking the punch against endwise play, said means including a cylindrical lock located in curved ways of the holder.

13. A punch adapted to operate in a direction transverse to its length and having along one side face thereof a rib-formed cutting portion having parallel side walls, a punch holder adapted to carry the punch, and means for locking the punch against 35 sidewise play.

14. A punch adapted to operate in a direction transverse to its length and having along one side face thereof a rib-formed cutting portion having parallel side walls, a punch holder adapted to carry said punch, means for locking the punch against endwise play, and means for locking the punch against sidewise play.

15. A punch adapted to operate in a direction transverse to its length and comprising 45 a lengthwise extending shank having at one side thereof a lengthwise extending rib provided with parallel side walls forming at the forward end of the punch a cutting 50 portion, said rib being located midway of the width of the shank and said punch having a tapered forward edge the apex of which terminates above the cutting edge of the rib, a punch holder adapted to carry

said punch, and coöperating means carried 55 by the punch and holder for locking the punch against endwise play.

16. A punch adapted to operate in a direction transverse to its length and comprising a lengthwise extending shank having at 60 one side thereof a lengthwise extending rib provided with parallel side walls forming at the forward end of the punch a cutting portion, said rib being located midway of the width of the shank and said punch having a 65 tapered forward edge the apex of which terminates above the cutting edge of the rib, a punch holder adapted to carry said punch, coöperating means carried by the punch and holder for locking the punch 70 against endwise play, and means for locking the punch against sidewise play.

17. The combination of a punch having along one side face thereof a rib-like cutting portion and a reinforcing body portion, a punch holder adapted to carry said punch, and means for locking the punch against endwise play and including a cylindrical lock located in transverse curved 75 ways of the holder.

18. The combination of a punch having a rib-like cutting portion and a reinforcing body portion, a punch holder adapted to carry said punch, and adjustable means for locking the punch against endwise play and 85 comprising a cylindrical lock located in curved ways of the holder and an adjusting screw passing through said lock and into the punch.

19. The combination of a punch having a rib-like cutting portion and a reinforcing body portion, a punch holder adapted to carry said punch, adjustable means for locking the punch against endwise play and comprising a cylindrical lock located in 95 curved ways of the holder and an adjusting screw passing through said lock and into the punch, and means for locking the punch against sidewise play.

Signed at Cleveland, in the county of 100 Cuyahoga and State of Ohio, this 8th day of December, 1914.
